UNITED STATES PATENT OFFICE.

CHARLES B. HATFIELD, OF ELMIRA, NEW YORK

FUEL-MIXING DEVICE FOR INTERNAL-COMBUSTION ENGINES.

1,130,278.

Specification of Letters Patent.

Patented Mar. 3, 1915.

Application filed January 7, 1914. Serial No. 810,860.

To all whom it may concern:

Be it known that I, CHARLES B. HATFIELD, of Elmira, in the county of Chemung and State of New York, have invented certain new and useful Improvements in Fuel-Mixing Devices for Internal-Combustion Engines; and I do hereby declare the following to be a full, clear, and exact description of the same, reference being had to the accompanying drawings, forming part of this specification, and to the figures and letters of reference marked thereon.

The class of fuel mixing devices to which the present invention is especially applicable is that class in which the devices embody in their construction a fuel jet orifices from which the fuel is discharged in a more or less globular condition, into a moving column of air; and the objects of the invention are to provide a construction whereby by the fuel will be reduced to a nebulized state and so distributed through the air as to make a homogeneous mixture, thus providing as it were a homogenized explosive mixture from which the fuel will not separate and deposit on the walls of the passages and cylinders to an injurious degree, but is so associated with the oxygen of the air as to at once enter into combustion when ignition is inaugurated.

Referring to the accompanying drawings, Figure 1 is a section in a vertical plane through a carbureter embodying the present improvement. Fig. 2 is a transverse section substantially on the line indicated at 2-2 in Fig. 1. Fig. 3 is an elevation. Figs. 4 and 5 are a plan and side elevation of the connection between the carbureter and engine, where it is desired that the duct shall feed vertically from the carbureter.

Like letters of reference in the several figures indicate the same parts.

The invention is illustrated in connection with a carbureter which, except for details of construction, is of a known type. As shown, said carbureter embodies a float chamber A to which liquid hydrocarbon is supplied, through an inlet pipe connection B and from which the hydrocarbon is discharged through a fuel nozzle C. The fuel level in the float chamber A is controlled by a float A¹, operating through a float lever A² upon any of the usual arrangements of float valve interposed in the fuel supply duct communicating with the pipe connection B and not specifically illustrated herein. The

nozzle C is located axially within a concentric air inlet or Venturi tube D, the discharge lips of the nozzle C being preferably located at the constricted portion of the tube. This Venturi tube forms one inlet branch of the conduit for conveying the mixture from the mixing device to the engine, the other branch through which air enters being formed by an extension E of the body of the device and controlled by a spring-pressed valve F opening inwardly in the well understood manner during the inspiration stroke of the engine. The two branches of the duct unite in the body G of the mixing device and form the conduit which leads to the engine. As shown in Figs. 1 and 3 the conduit is in part formed by a pipe connection H, the face of which may be adapted for connection with the ordinary manifold in any usual way. Where the conduit is adapted to lead into the lower end of a vertical manifold connection an elbow pipe connection I shown in Figs. 4 and 5 may be employed, both arrangements providing for the location of a throttle valve K in the conduit where it may control the effective flow of mixture therethrough. For regulating the quantity of liquid fuel which is allowed to discharge into or be supplied to the air passing through the Venturi tube branch of the conduit, a needle valve K¹ is provided having a stem K² extending up into the conduit and preferably across the same to the upper side of the body where it is provided with an adjusting knob K³, the intermediate portion of the stem being threaded as shown, and the knob provided with means such as the spring finger k whereby it may be adjusted and locked in its adjusted position.

In accordance with the present invention, the liquid fuel which is supplied from the nozzle in a more or less globular condition is effectually broken up and nebulized by the disruptive action of the multiplicity of relatively fine vibratory baffle rods or wires mounted in the conduit, so as to intercept the globular fuel and nebulize the same, but at the same time offer the least possible resistance or obstruction to the flow of air through the conduit. As an important feature of this part of the invention, the initial nebulization of the fuel discharged from the nozzle is effected at the time when the fuel exists in the air in the densest condition, that is to say, in the Ven-

turi tube branch of the mixer, and before the fuel and air entering through the Venturi tube is combined with the air entering through the other branch of the conduit.

5 This result is effected by a multiplicity of relatively fine resilient baffle rods or wires M, located radially in the Venturi tube branch of the conduit above the fuel nozzle. The nebulizing effect is furthermore, augmented and particles which might have escaped the action of the vibratory baffle wires in the Venturi tube are caught by a secondary system of such wires located in the main portion of the conduit and preferably immediately in front and rear of the throttle valve. As shown in Figs. 1, 3 and 4, a multiplicity of these relatively fine resilient baffle rods or wires are located at N and N', one body of them being located in front of 15 and the other in rear of the throttle valve.

In all cases the resilient and vibratory baffle wires are supported rigidly at one end only and project radially into the conduit or branch of the conduit as the case may be, 20 preferably in staggered relation so that little or no opportunity is afforded for any of the fuel to pass the same without striking the wires and, by the vibratory action and impact being split up into the finest subdivisions.

25 As a convenient and important feature of the construction the vibratory baffle wires are mounted in annular carriers which are made to fit the portion of the device which is to support the same; thus, as shown in Fig. 1, the baffle wires M are mounted in an annulus m, which in turn is mounted on the valve stem K', and consequently the baffle wires may all be assembled on their annulus 30 and attached to the valve stem in the most convenient manner. In the case of the baffle wires N and N' they are mounted in their supporting annuli n and n', which latter are adapted to fit in the conduit and be held 35 therein by set screws O or shoulders O', as desired.

By mounting the vibratory baffle wires on annular supports which are subsequently placed in position in the mixer, it is obvious 40 that a very great advantage results both in the convenience of manufacture and in the ability of the workmen to locate and position the baffle wires with accuracy, as well as to fasten them securely in place without destroying the temperature of the material 45 which might, to a certain extent interfere with the vibratory action. The baffle wires so called, it will be understood, are set into vibratory action by the flow of air past and around the same, and they are preferably of 50 different lengths, thus insuring an active vibratory action with the air flowing at different speeds. The rate of vibration, it is believed, should be as high as it is consistent 55 with a range of movement which will project the disrupted particles away from the wires so that there will be no tendency of the liquid fuel to adhere and be conducted to the walls of the conduit. In fact it is demonstrable that a wire supported at one end and free at the other end, when set in vibratory motion, will cause any liquid material striking the same to tend to move toward the free end of the wire, and this action in the present apparatus results in all 60 of the liquid fuel being thrown off of the wires and projected in disrupted condition into the body of air traveling between the wires. The result is a most thorough homogenizing of the mixture as well as a nebulizing of the liquid fuel, so that practically none of the particles remain in a globular form which will separate out by gravity or by centrifugal action in passing to the engine cylinder or while within the cylinder 65 under the influence of the piston action.

Having thus described my invention, what I claim as new and desire to secure by Letters Patent of the United States is,—

1. In a fuel mixer for internal combustion engines, the combination with the conduit through which the mixture is conducted to the engine having two air entrance branches, and means for supplying liquid fuel to one of said branches, of a multiplicity 90 of fine vibratory baffle rods located in said last mentioned branch for nebulizing the liquid fuel supplied thereto before the same is combined with the air entering through the other branch.

2. In a fuel mixer for internal combustion engines, the combination with the conduit through which the mixture is conducted to the engine and a liquid fuel nozzle opening into said conduit, of a valve for said nozzle 105 having its stem extending into the conduit and a multiplicity of vibratory baffle rods mounted on said stem and projecting into the conduit in position to nebulize the liquid fuel supplied by the nozzle.

3. In a fuel mixer for internal combustion engines, the combination with the conduit through which the mixture is conducted to the engine, of a separate annulus mounted in said conduit and a multiplicity of radially arranged vibratory baffle rods fixed at one end in said annulus whereby the rods and annulus may be formed complete and subsequently positioned in the conduit.

4. In a fuel mixer for internal combustion engines, the combination with the conduit through which the mixture is conducted to the engine having two air entrance branches, one of said branches being in the form of a Venturi tube, a liquid fuel nozzle located at 120 the constricted portion of said tube, and a multiplicity of vibratory baffle rods mounted in said Venturi tube branch of the conduit above the liquid fuel nozzle and in position to nebulize the fuel passing from said 125

nozzle before said fuel combines with the air entering the other branch of the conduit.

5. In a fuel mixer for internal combustion engines, the combination with the conduit through which the mixture is conducted to the engine having two air entrance branches, one of said branches being in the form of a Venturi tube, and a liquid fuel nozzle located at the constricted portion of said tube, of a 10 valve for said nozzle having a stem extending transversely across the conduit, and a multiplicity of vibratory baffle wires mounted radially on said stem in position to nebulize fuel issuing from the nozzle.
- 15 6. In a fuel mixer for internal combustion engines, the combination with the conduit through which the mixture is conducted to the engine having two air entrance branches, one of said branches being in the form of a 20 Venturi tube, and a liquid fuel nozzle located at the constricted portion of said tube, of a multiplicity of radially arranged resilient and vibratory baffle rods located in the upper portion of said tube above the fuel nozzle, and a system of radially arranged re-

silient and vibratory baffle rods mounted in the body of the conduit beyond the point where the two branches unite, whereby the fuel will be preliminarily nebulized in the Venturi tube branch in the conduit, and again subjected to the action of the vibratory baffle rods when combined with the air entering through the other branch of the conduit.

7. In a fuel mixer for internal combustion engines, the combination with the conduit through which the mixture is conducted to the engine, of a plurality of separate annuli mounted in said conduit, and each having a multiplicity of radially arranged vibratory baffle rods fixed thereto at their outer ends only and projecting radially toward the center of the conduit, whereby the annuli and rods may be formed complete in themselves and subsequently positioned in the conduit.
